UNITED STATES PATENT OFFICE.

RICHARD C. LAMBERT, OF NORTH MIDDLEBOROUGH, MASSACHUSETTS.

TACKING-TOOL.

SPECIFICATION forming part of Letters Patent No. 412,762, dated October 15, 1889.

Application filed May 31, 1889. Serial No. 312,748. (No model.)

To all whom it may concern:

Be it known that I, RICHARD C. LAMBERT, of North Middleborough, county of Plymouth, State of Massachusetts, have invented an Improvement in Tacking-Tools, of which the following description, in connection with the accompanying drawings, is a specification, like letters on the drawings representing like parts.

10 This invention has for its object the production of a tacking tool or apparatus to be operated by hand or otherwise for driving, one after another, headed tacks or nails taken from a raceway supplied from a hopper forming part of the tool or apparatus.

15 The improved tacking tool or apparatus herein shown includes a hopper, a raceway, a conductor between the hopper and raceway, a receiver outside the raceway, a case or sleeve having a driveway or throat to receive tacks from the raceway, a driver-bar, a driver, and a separator actuated by the driver-bar, and having two blades located in substantially the same vertical plane, one of 20 the said blades entering between the endmost tack of the raceway and the one next to it when the driver is acting on the head of and driving a tack and until the end of the driver in its ascent rises to the level of the 25 top of the raceway, the said blade keeping the tack next to be driven pressed against the side of the driver next the blade, so that the said tack, cut off from the row of tacks, immediately drops into the driver-passage as 30 soon as the lower end of the driver in its ascent passes above the head of the said tack. Just as the tack referred to enters the driver-passage under the rising driver the detaining-blade with its point comes in contact with a 35 part of the endmost tack in the raceway and prevents it leaving the raceway, but as soon as the driver in its next descent meets the head of the tack to be driven, the two blades move in the same direction far enough to re- 40 move the detaining-blade from the tack at the end of the raceway and to bring the space between the separating and detaining blades opposite the said tack, when it passes through the said space and is stopped by contact with 45 the side of the driver, and then in their further movement in the same direction the separating-blade enters fully between the tack

resting against the driver and the next tack back of it in the raceway.

Figure 1, in side elevation partially broken out, represents a tacking tool or apparatus embodying my invention. Fig. 2 is a vertical section of the tool or apparatus shown in Fig. 1, along the line x , looking to the left, the case or sleeve and the hopper above the separator being in vertical section. Fig. 3 is a section of the raceway, the receiver, and parts connected therewith in the line x^2 , Fig. 1, looking to the left. Fig. 4 is a section in line x^4 , Fig. 1. Fig. 5 is a partial section in the line x^3 ; Fig. 6, a top or plan view of the hopper; and Fig. 7, a view of the apparatus, looking at it in the direction of the arrow, Fig. 2, chiefly to show the relative positions of the blade to the raceway and the driver-passage and driver.

Referring to the drawings, a represents a substantially tubular case or shell, which, as herein shown, serves as a hand-piece, it having at its lower end a nose a' , provided with a throat a^2 , down through which passes the tack or nail taken from the end of the raceway b , connected with the said case as the tack is to be driven. The case a has secured to it a spring a^3 , one end of which acts upon a yielding stop a^4 , (shown by dotted lines, Fig. 1,) extended partially across the opening in the throat, the said stop arresting the tack when it drops into the throat and supporting it until after the head of the tack is struck by the driver c in its descent to drive a tack. The driver c is connected to the lower end of a driver-bar c' , extended up through the case or sleeve, where it is shown as provided with a head c^8 , to be struck by a hammer or otherwise. The driver-bar has a slot, as c^4 , through which is extended a pin, as c^5 , which is held in a nut c^6 , screwed upon or otherwise secured to the upper end of the sleeve a . The driver-bar has a shoulder, as c^7 , which is acted upon by the spring c^8 , surrounding the driver-bar, the lower end of the said spring resting upon a shoulder c^9 , farther down in the sleeve, (see Fig. 2,) the said spring normally acting to keep the driver-bar and driver in their elevated position, as shown in the said figure. The sleeve a has a shoulder 4 , upon which rests the bottom of the box or hopper d , (herein shown as substantially rectangular

in shape,) the said box or hopper, a plan of which is shown in Fig. 6, having a central opening, as 8, which surrounds the sleeve *a*, the top of the box being acted upon by the 5 nut *c*. The box has a suitable cover or door, as *d*', which when sprung aside permits tacks to be placed in bulk in the box. This box has preferably an inclined bottom piece, as 10 *d*', and at that end of the box where the bottom is most inclined the box has attached to it a conductor *d*², made in the form of a tube, which is extended down to and is connected with the raceway *b* at its outer end. This 15 raceway has connected with it a receiver, as *e*, it being shown as a sort of tubular jacket to receive any loose tacks which might fall out of the raceway. The end of the raceway next the conductor is covered by a hood *e*', the shape of which is best shown in Fig. 3, it 20 having curved inner walls to direct the tacks into the slot of the raceway. The points of those tacks which fall correctly into the slot 10 (see Fig. 3) of the raceway rest upon the upper portion of the raceway and pass down 25 the raceway under the cover-plate 12 to the end thereof; but those tacks which do not enter with their bodies the slot of the raceway fall off the raceway after passing the cover *e*', and enter the receiver, from which 30 they may be removed in any usual manner and be poured back into the hopper. The sleeve *a* supports a stud *f*, which constitutes the fulcrum for the separator *f*', the latter consisting, essentially, of a slotted plate having 35 long and short blades, to be described. The slot 13 in the separator receives in it a pin 14, extended from a collar or projection secured to the driver-bar and extended outwardly therefrom through a slot 16. The slot 40 17 in the separator is of arc shape and receives in it a stud-screw 18, which constitutes a guide for the separator in its movements about the stud *f*. The separator has two blades 20 and 21, the one 20 being designated 45 the "separator-blade" and the one 21 the "detaining-blade." They are each connected with the separator by suitable screws or rivets 22, and are shown as curved at bottom and top, the two ends of the blades being 50 somewhat separated from each other, and being in substantially the same vertical plane, the space between the blades serving as a passage-way to permit the endmost tack of the row of tacks in the raceway to drop off 55 one after another and pass through the said slot, as described. The blades of the separator *f*' are located a short distance at one side from the throat or driver passage, the distance being sufficient to leave a space between 60 the separator-blade 20 and the side of the driver just large enough to receive the tack next to be driven, the distance referred to depending upon the diameter of the body and head of the tack or nail.

65 Herein it will be noticed that the case or sleeve *a*, in which the driver-bar reciprocates, is extended through the hopper *d*, near its

center, so as to leave narrow channels or passage-ways 121 between the said sleeve and the interior of the hopper, through which the 70 tacks or nails may pass, the said passage-ways preventing the tacks or nails being fed through too rapidly into the raceway.

It is obvious that the receiver might be omitted should it not be desired to save the 75 tacks which fail to correctly enter the raceway.

I do not desire to limit my invention to the exact form of spring used to actuate the driver.

The separator herein described might be employed in connection with a driver and raceway in a power-actuated nailing-machine, and yet operate substantially as described herein.

8c I claim—

1. In a tacking apparatus, the hopper to receive tacks or nails, a raceway, a conductor between the hopper and raceway, and the case or shell and driver-bar, and driver, combined with the separator having separating and detaining blades 20 21, located in substantially the same plane, and operating substantially as described.

2. The raceway, the case or sleeve having 95 the driver passage or throat, and the driver and driver-bar, combined with the separator having separating and detaining blades 20 21, located in substantially the same plane, and having a space between their ends for 100 the passage of a tack or nail from the end of the raceway into position against the side of the driver, the separating-blade keeping the tack against the side of the driver while the latter is completing the driving of a tack or 105 nail and is being partially elevated, substantially as described.

3. The raceway, the case or shell in communication therewith, the driver, and the driver-bar having a projection and stud, combined with a separator having a slot, as 110 13, and two blades 20 and 21, to operate substantially as described.

4. The case or shell, the driver-bar, and driver therein, combined with the hopper, 115 through which the said case or shell is extended, a raceway, and a conductor connecting said hopper and raceway, to operate substantially as described.

5. In a tacking apparatus, the raceway, the 120 case or shell, the driver-bar, and driver therein, combined with the hopper and conductor, the raceway being provided with the cover having a concave or curved interior surface, and located immediately above the slot in the 125 raceway, to operate substantially as described.

In testimony whereof I have signed my name to this specification in the presence of two subscribing witnesses.

RICHARD C. LAMBERT.
